UNITED STATES PATENT OFFICE.

GEORGE E. COOPE, OF NEW YORK, N. Y.

EYEGLASS-CASE.

SPECIFICATION forming part of Letters Patent No. 781,809, dated February 7, 1905.

Application filed July 21, 1904. Serial No. 217,472.

To all whom it may concern:

Be it known that I, GEORGE E. COOPE, a citizen of the United States, and a resident of New York, in the county of New York and State of New York, have invented certain new and useful Improvements in Eyeglass-Cases, of which the following is a specification.

My invention relates more particularly to that class of eyeglass-cases which are formed with a dome in the lid or cover, and designed more especially for holding eyeglasses which are provided with offset nose-guards; and my invention consists mainly in constructing the body of the case of less width than the space occupied by the lenses and their attached nose-spring and in constructing the cover so that it will inclose the nose-spring and when the cover is opened the central portion of the cover will fall away from the nose-spring, leaving it projecting beyond the back or bottom of the main body of the case.

The invention also consists in the construction of the cover and in its combination and arrangement with the body of the case, all as hereinafter described and claimed.

In the accompanying drawings, to which reference is made and which form a part of this specification, Figure 1 is a plan view of an eyeglass-case made in accordance with my invention, showing the lid or cover partially open and showing a pair of eyeglasses in the case. Fig. 2 is a like view of the case, showing the cover closed. Fig. 3 is a transverse sectional elevation taken on line 3-3 of Fig. 1 and showing in dotted lines the lid fully opened, and Fig. 4 is an inside plan view of the metal or other stiff body of the cover detached.

In the drawings, 2 designates the body of the case, and 3 the lid or cover, which is hinged at 4 to the body, preferably by the lining 5 of the case and by the outside covering 6.

The body 2 of the case is provided with a tray 7 and with the end pieces 8 8, which are turned up at the ends of the substantially flat back or bottom 9 of the body of the case, the core of which is metal or other stiff material. The said back or bottom 9 of the case is the width of the lenses used in standard eyeglasses, and the tray is shown as provided with a fas-

tening device to engage with a complementary fastening device shown on the lid or cover.

The lid or cover 3 of the case is formed in the center with an elevated portion or dome 10, the end portions 12 12 of the cover which close over the lenses being depressed substantially to the same level as the upper edges of the end pieces 8 8. The edges 13 13 of the cover are parallel in the hinge with the rear edge 14 of the body of the case. Intermediate of the said edges 13 13 is formed an enlargement 15, which forms a chamber 15^a, as shown clearly in Fig. 3. When the cover is closed, the bottom of the chamber 15^a in the cover is parallel with the bottom of the body of the case, and when the cover is opened it turns back below the bottom of the body of the case, and should the cover be turned back, as shown in dotted lines in Fig. 3, it abuts against the back of the body and prevents overstraining of the hinge. The metal part of the cover is formed at its hinge edge, as shown in Fig. 4—that is, it is by preference formed with the said straight edges 13 13 and with the intermediate curved and dished extension 16, the edge of which latter is turned back to form a flange 17, the edge 17^a of which is substantially parallel with the edges 13 13, so as to form a part of the hinge. When the cover is open, the falling back of the chamber 15^a enables the user to grasp the nose-spring of the eyeglasses for conveniently removing them from the case, and when the cover is closed a firm support parallel with the bottom of the body of the case is afforded for the nose-spring.

Ordinarily when eyeglasses are placed in an eyeglass-case the user presses his forefinger back on the open cover while the body of the case is held between the thumb and second finger. In this the tendency is to press the cover back beyond bounds, thus straining, weakening, and finally breaking the hinge. By my construction the enlargement of the cover prevents straining of the hinge in the manner stated and greatly prolongs the life and usefulness of the case, and, furthermore, I am enabled to reduce the width of the body of the case practically to the width of the lenses.

Having thus described my invention, what I claim as new, and desire to secure by Letters Patent, is—

1. An eyeglass-case, comprising a main body provided with a tray at one edge and a cover hinged to the opposite edge to close upon the tray, the cover being formed with a central dome intermediate of substantially flat end portions of the cover, said dome projecting beyond the hinge edges of the cover to form an edge chamber in the cover to inclose the nose-spring of the glasses, substantially as described.
2. An eyeglass-case comprising a main body provided with a tray at one edge and a cover hinged to the opposite edge, the cover being formed with a central dome intermediate of flattened end portions whose edges are straight at the hinge, said dome projecting be-

yond said straight edges and having a flange 20 projecting inward toward the hinge, substantially as described.

3. An eyeglass-case comprising a main body of less width than the lenses and metal mountings of eyeglasses the said body being 25 provided with a tray and with end pieces, in combination with a cover hinged to said body and arranged to close upon the said tray and end pieces the cover being formed with straight edges 13, 13, and with an enlargement intermediate of said straight edges and projecting beyond the hinge of the cover, substantially as and for the purposes described.

GEORGE E. COOPE.
